(57) **CLAIM**

The ornamental design for an alignment cover for an electrical connector, as shown and described.

DESCRIPTION

FIG. 1 is a top plan view of an alignment cover for an electrical connector;

FIG. 2 is a front view of the alignment cover;

FIG. 3 is a bottom plan view of the alignment cover;

FIG. 4 is a rear view of the alignment cover;

FIG. 5 is a right side view of the alignment cover;

FIG. 6 is a front, top and right side perspective view of the alignment cover;

FIG. 7 is a front, bottom and right side perspective view of the alignment cover; and,

FIG. 8 is an additional perspective view of the alignment cover, with the broken-line disclosure of environmental structure being for illustrative purposes only and forming no part of the claimed design.

A left side view of the electrical connector is omitted because it is shown symmetrically to the right side view shown in FIG. 5.

The electrical connector with which a plurality of cables are connected as shown in FIG. 8 do not form any part of the alignment cover.
